UNITED STATES PATENT OFFICE

1,932,796

GREASE RAM

Norris F. McNaught, Chicago, Ill., assignor to
Duro Metal Products Company, Chicago, Ill.,
a corporation of Illinois

Application May 18, 1931. Serial No. 538,138

2 Claims. (Cl. 184—105)

My invention relates to a grease ram, and is particularly concerned with improved means for braking and limiting outward movement of the plunger of such a device.

5 Grease rams of the kind to which this invention relates ordinarily are employed to force fresh grease through bearings when, due to the accumulation of hard grease in the bearings or for other reasons, the ordinary grease gun will not 10 serve the purpose. The procedure, in using such a grease ram, is to fill the ram with grease, substitute it for the grease cup or lubricating fitting with which the bearings ordinarily are equipped, and then sharply strike the impact head of the 15 ram a blow with a hammer or other tool to force an adequate supply of grease into the bearing under very high pressure.

In the accompanying drawing illustrating a preferred embodiment of my invention

20 Fig. 1 is a view of the grease ram, partly in elevation and partly in axial section, the extended position of the plunger being illustrated by full lines and its depressed position being indicated by dotted lines;

25 Fig. 2 is a section taken on the line 2—2 of Fig. 1 and looking in the direction indicated by the arrows; and

30 Fig. 3 is a view corresponding to Fig. 2, which may be regarded as taken when the plunger is in the depressed position indicated by dotted lines in Fig. 1.

Similar characters of reference refer to similar parts throughout the several figures.

In the drawing, reference numeral 4 indicates 35 a barrel which, throughout the greater portion of its length, preferably is hexagonal to facilitate its application to and disengagement from an internally threaded passage leading to a bearing on an automotive vehicle or other piece of machinery, i. e. the internally threaded opening into which a grease cup or lubricating nipple ordinarily is threaded. The barrel is provided with an externally threaded nipple 5 affording a passage 40 6 for the discharge of grease from the barrel bore 7.

45 At its upper end the barrel 4 is provided with a short counterbore coaxial with the main barrel bore 7 to afford an annular compartment 8 housing a brake-detent 9 presently to be discussed in more detail. The annular compartment 8 is defined by the upper portion of the barrel, the ram plunger 10 and an internally threaded collar 11 which cooperates with external screw threads 55 formed on the upper end of the barrel, and is

provided with a central aperture through which the ram plunger 10 extends.

At its upper or outer end the ram plunger 9 is provided with an impact head or anvil 12 adapted to be struck by a hammer or other tool 60 in operating the ram to force grease into a clogged bearing.

Near its lower or inner end the plunger 10 is provided with an annular groove which generally is V-shaped, one wall of this V-shaped groove, 65 indicated at 13, being located in a plane at right angles to the axis of the plunger 10, and the other wall of the groove, indicated at 14, constituting the frustum of a cone having its axis coincident with the axis of the plunger 10. 70

The brake-detent 9 is in the form of a single piece of spring wire conformed to present an annular portion 9—a occupying the annular compartment 8 to which reference previously was made, the ends 9—b, 9—b of this single piece of 75 spring wire curving inwardly from the annular portion 9—a to engage and embrace the plunger 10.

In using the ram, the plunger is placed in the dotted line position of Fig. 1 and the nipple 5 80 is immersed in a supply of lubricant. The plunger then is moved to the full line position of Fig. 1 to fill the barrel bore 7 with lubricant. When, on its outward movement, the plunger reaches the position shown in Fig. 1, the inwardly curving extremities 9—b, 9—b of the brake-detent snap into the annular groove of the plunger, and by their engagement with the wall 13 of such groove prevent the plunger from being entirely withdrawn from the barrel. The barrel nipple 5 now is 90 threaded into an opening associated with the bearing to be lubricated, and the impact head 12 is struck a sharp blow with a hammer or other suitable tool to depress the plunger and force grease under high pressure through the nipple 5. 95 When the plunger thus is depressed, the extremities 9—b, 9—b of the brake-detent ride up the conical wall of the plunger groove onto the cylindrical surface of the plunger. 85

Normally, when the ram is not in use, the 100 plunger will occupy the dotted line position of Fig. 1, in which event the extremities 9—b, 9—b of the brake-detent will occupy the positions shown in Fig. 3, where they brake but do not prevent outward movement of the plunger. 105 However, as previously pointed out, the said extremities 9—b, 9—b of the brake-detent do act positively to prevent outward movement of the plunger from the full line position of Fig. 1.

110 A salient advantage of the particular form of

brake-detent herein shown and described is that there is practically no tendency for the inwardly curving extremities 9—b, 9—b thereof to take a set in the positions of Fig. 3, even though the 5 ram, with plunger depressed, may remain unused for many months at a time. It has been quite a problem, within my experience, to provide a simple form of brake-detent which does not have a tendency to take a set when its plunger en- 10 gaging parts are for long periods of time out of the positions which they occupy when cooperating with the annular groove of the plunger.

Having thus illustrated and described the preferred embodiment of my invention, what I claim 15 is new and desire to secure by Letters Patent of the United States, is:

1. In a grease ram, a barrel adapted for connection with a bearing, a plunger operating in the barrel and projecting from one end thereof, the 20 end of the barrel from which the plunger projects being counterbored to provide an annular seat, a collar closely surrounding the plunger and threaded upon the last mentioned end of the barrel, the said annular seat, collar, and 25 plunger defining a detent-brake compartment, a detent-brake freely disposed in said compartment, said detent-brake consisting of a piece of spring wire conformed to define a circle and having its ends crossing each other and curving in-

wardly from said circle to define an expansible plunger embracing oval lying within said circle, the plunger being provided adjacent its inner end with an annular groove having a conical wall and an abutment wall, the inwardly curving ends of the detent-brake being adapted to ride upon said conical wall into engagement with the abutment wall to limit the outward movement of the plunger and to be guided out of the said groove by the said conical wall when the plunger is struck 85 inwardly.

2. In a grease ram comprising a barrel and a plunger, a groove formed in the plunger near its inner end and providing an abutment wall and a detent-brake located at the end of the barrel from which the plunger projects and lying wholly within the confines of said barrel, said detent-brake being in the form of a piece of spring wire conformed to define a circle and having its ends crossing each other and curving inwardly from 90 said circle to define an expansible plunger embracing oval lying within said circle, the inwardly curving ends of the detent-brake being adapted to ride into engagement with the abutment wall to limit the outward movement of the 100 plunger and to be guided out of said groove when the plunger is struck inwardly.
